United States Patent Office

Des. 191,168
Patented Aug. 22, 1961

191,168

NOVELTY CHEST OR SIMILAR ARTICLE

Stevenson Peter Clark, 3185 Royal Road,
Coconut Grove, Miami, Fla.

Filed July 26, 1960, Ser. No. 61,533

Term of patent 3½ years

(Cl. D33—6)

FIG. 1 is a front elevational view of a novelty chest or similar article showing my new design;

I claim:

The ornamental design for a novelty chest or similar article, as shown.
